UNITED STATES PATENT OFFICE.

WILLIAM J. KEEP, OF DETROIT, MICHIGAN, ASSIGNOR TO THE MICHIGAN STOVE COMPANY, OF SAME PLACE.

VENTILATING-STOVE.

SPECIFICATION forming part of Letters Patent No. 375,359, dated December 27, 1887.

Application filed March 22, 1887. Serial No. 231,964. (No model.)

To all whom it may concern:

Be it known that I, WILLIAM J. KEEP, a citizen of the United States, residing at Detroit, in the county of Wayne and State of Michigan, have invented certain new and useful Improvements in Ventilating-Stoves, of which the following is a specification, reference being had therein to the accompanying drawings, in which—

10 Figure 1 represents a perspective view of a stove constructed according to my invention; Fig. 2, a horizontal section through the line xx ; Figs. 3, 4, 5, 6, 7, and 8 are details that will be more fully described hereinafter.

15 This improvement relates, mainly, to ventilating-stoves; and the invention consists in the construction, arrangement, and combination of parts, hereinafter more particularly described, and then more definitely pointed out 20 in the claims.

The accompanying drawings show my invention carried out on an ordinary sheet-iron round stove modified to suit my invention; but I do not intend to limit myself to this construction, as the stove may be made of any 25 shape or material without departing from the spirit of my invention.

In said drawings, A represents the base, supported on legs B, as usual, having an ash-pit, C, closed by a door, D, having a hood, E, which may be provided with a damper, index, &c., similar to that shown and claimed in my application No. 227,806, filed February 16, 1887, which is designed to allow the cold 35 air that lies nearest the floor to be taken up into the ash-pit, and to govern its admission thereto. From the base A the fire-pot casing F rises and supports a ring, G, that carries the sheet-metal jacket H, above which is the 40 top I, of any suitable form, either ornamented or plain. Between the base A and ring G are two flues, J K, formed in any suitable manner, but preferably by attaching plates to the outside of the fire-pot or casing, which flues 45 communicate through holes in the ring G with other flues, L M, that partially surround the door N, and the walls of which preferably form the frame of the doorway thereof. These flues may be formed in the manner shown in Fig. 2 50 by riveting castings on the face of the jacket; or they may be formed in the frame of the

doorway itself, as shown in Figs. 7 and 8. The upper end of the flue L terminates in the openings l; but the flue M terminates in an opening that allows the air to pass inside the stove, as 55 shown in Fig. 3. The flue J is in communication through an opening in the base A with a tube, O, the lower end of which is over an opening in the floor that forms one end of a passage (shown in dotted lines) under the 60 floor, and whose other end is in connection with the outside air. At the lower end of this pipe, and at one side thereof, is an opening, o, that is ordinarily closed by a gate, P, which, however, can be turned down, as shown in 65 dotted lines, so as to shut off the outside air and admit that from the room.

Between the bottom of the ash-pit and the base A there is a sliding box or valve, Q, having in its top an opening, q, and in its bottom 70 another opening, q', which openings, when the valve is pushed to the left, as in Figs. 3 and 4, register, respectively, with the opening in the base under the flue K, and with an opening, c, in the bottom of the ash-pit. (Shown in 75 dotted lines in Figs. 3 and 6.) When the valve is moved to the left, as shown in Figs. 5 and 6, the bottom of the box covers the opening c, and the opening in the base A under the flue K is uncovered, thus leaving said flue 80 K and the ash-pit in full communication with each other and with the inside of the stove above the fire.

From the above description the operation will be obvious and hardly needs a detailed 85 description, and it will therefore suffice to say that as air enters the flues J L from the outer atmosphere it becomes heated and lighter, and thus rises through the openings l into the room, and up to the upper part of the room, displacing the cold air there, which, being the heaviest, descends to the floor and is drawn into the fire through the opening in the ash-pit door. Any cold air which may come into 90 the room through an open door will, owing to its greater gravity, also descend to the floor, and will be drawn through the ash-pit into the fire to support combustion.

When the valve Q is in the position shown in Figs. 3 and 4, the air from the room will 100 pass up through the flues K M into the stove above the fire, as shown by the arrows, and

thus the cold air from the floor will be rapidly drawn away. When the valve Q is set to the left, as shown in Figs. 5 and 6, any air that may leak into the ash-pit through the crevices, instead of passing through the fire, will take the path of least resistance and pass into the stove above the fire through the flues K M, and thus check the fire.

From the above description it will be seen that the ventilation of the room is under perfect control, and that I obtain the largest amount of ventilation and warmth with the least amount of fuel, as the very coldest air is always drawn away from the floor to feed the fire, while the pure air from the outside is heated as it passes into the room, instead of entering the room in the form of cold drafts through crevices in the doors and windows, as is usual with the stoves ordinarily employed.

Having thus set forth one way of carrying out my improvement, but without limiting myself to the construction shown, I claim—

1. A stove having a flue communicating with the same above the fire-pot at one end and with the ash-pit and the outer air at the other end, in combination with a valve for controlling the inflow of air to said flue from either the ash-pit or the outer air, substantially as described.

2. The combination, with a stove-easing, of a door-frame attached thereto and formed with external air-flues having openings above and below for the ingress and egress of the air, substantially as described.

3. The combination, with a stove and the casing thereof, of a doorway-frame constructed to form two passages parallel with said casing, one of which forms a pure-air heater and communicates with the air in the room at each end, and the other a foul-air flue communicating with the fire-chamber and provided with an ingress-opening at a point below its egress-opening, substantially as described.

4. The combination, with a stove and with the casing thereof, of a doorway-frame having passages on each side parallel with the casing, and suitable ingress and egress openings, one

communicating with the room or external atmosphere, as desired, and the other with the room and ash-pit, and valves for controlling the admission of air to one of said flues from the room or the ash-pit and the other flue from the room or external atmosphere, substantially as described.

5. As a new article of manufacture, a stove-door frame formed with vertical flues, the upper end of one flue terminating in the openings l and the other adapted to communicate with an opening in the wall of the stove, and both provided with suitable openings to admit the air, and adapted to serve as and for the purpose specified.

6. The combination, in a stove, of an air-flue communicating with the fire-chamber, a base, A, having an opening under said flue, an ash-pit, C, having an opening through which air may pass into said flue, with the valve Q, having corresponding openings and adapted to connect the flue with the ash-pit or the room, as desired, substantially as described.

7. The combination, with the fire-pot casing and air-heating flues J K thereon, of the jacket and the door-frame attached thereto and provided with flues L M, communicating with the tops of said flues J K, the flue L communicating with the air in the room and flue K communicating with the fire-chamber, as and for the purpose specified.

8. The combination, with the fire-pot casing and air-heating flues J K, of the ring G, having openings communicating with said flues, the jacket, and the door-frame having air-heating flues L M, communicating with the flues J K, the flue L communicating with the air in the room and the flue M communicating with the interior of the jacket, substantially as and for the purpose specified.

In testimony whereof I affix my signature, in presence of two witnesses, this 18th day of March, 1887.

WILLIAM J. KEEF.
